United States Patent Office

Des. 193,087
Patented June 26, 1962

193,087

SHOE

Beth Levine, 59 W. 12th St., New York, N.Y.

Filed Feb. 14, 1962, Ser. No. 68,817

Term of patent 14 years

(Cl. D7—7)

FIG. 1

FIG. 2

I claim:

The ornamental design for a shoe, substantially as shown.
